UNITED STATES PATENT OFFICE.

JOSEPH VALIND, OF GLADSTONE, MICHIGAN, ASSIGNOR OF ONE-HALF TO AUGUST BLOMSTROM, OF WELLS, MICHIGAN, AND ALFRED GRANT, OF ESCANABA, MICHIGAN.

WRENCH.

1,105,725.

Specification of Letters Patent.

Patented Aug. 4, 1914.

Application filed November 15, 1913. Serial No. 801,219.

To all whom it may concern:

Be it known that I, JOSEPH VALIND, a citizen of the United States, residing at Gladstone, in the county of Delta and State of Michigan, have invented certain new and useful Improvements in Wrenches, of which the following is a specification, reference being had to the accompanying drawings.

This invention relates to new and useful improvements in wrenches and the primary object of my invention is to provide an adjustable wrench that can be quickly and easily manipulated to place the adjustable jaw of the wrench at a desired position upon the shank relatively to the fixed jaw thereof, this object being accomplished by means of a mechanism which is entirely concealed within the shank.

Another object of the invention is the provision of a wrench of the above character which will possess advantages in points of efficiency and durability, is inexpensive of manufacture and at the same time is simple in construction and operation.

With the above and other objects in view, the invention consists in the novel features of construction and the combination and arrangement of parts to be hereinafter more fully described, pointed out in the claim and shown in the accompanying drawings, in which—

Figure 1 is a side elevation of a wrench constructed in accordance with my invention; Fig. 2 is a partial detail longitudinal sectional view; Fig. 3 is a transverse sectional view taken on the line 3—3 of Fig. 1; Fig. 4 is a transverse sectional view taken on the line 4—4 of Fig. 2; Fig. 5 is a transverse sectional view taken on the line 5—5 of Fig. 2.

Referring more particularly to the drawings, 1 indicates the rigid shank of my improved wrench having a handle portion 2 formed integral at one end thereof and a rigid jaw 3 formed at the other end thereof.

The shank as clearly illustrated in the accompanying drawings is preferably formed flat and the handle member 2 which is formed integral therewith is preferably of oval shape in form, as illustrated and is provided upon one side thereof with oppositely disposed shoulders 4 forming a reduced portion 5 in which is provided a recess 6 to receive a screw 7 provided with a substantially rectangular bore 8. The reduced portion 5

is provided with a longitudinal bore 9 which is adapted to communicate with the recess 6 and arranged in alinement with the central bore 8 of the screw 7. A substantially rectangular rod 10 is arranged within the bores 8 and 9 and is provided upon its outer end with a knob 11 whereby the same may be readily turned when desired to impart motion to the sleeve 6. The reduced portion 5 is provided beyond the recess 6 with a bore 12 in which the tapering end of the rod 10 is disposed so as to prevent lateral movement of the screw 7 when the rod is arranged in position.

Arranged alongside the rigid shank 1 is a movable shank 13 which is preferably of the same form as the rigid shank and provided at its outer end with a jaw 14 and is further provided at its inner end with a substantially semicircular portion 15 having a concave recess 16 upon the inner face thereof which is provided with the screw threads 17 adapted to co-act with the screw 7 whereby upon rotation of said screw the movable jaw 14 will be adjusted toward or away from the rigid jaw 3. Spaced sleeves 18 are carried by the movable shank 13, one of said sleeves being arranged adjacent the jaw 14 and adapted to inclose the shank portions 1 and 13. The other of said sleeves is carried by the inner end 15 of the movable shank and is adapted to inclose the handle portion 2 of the rigid shank so that the two shanks may be securely held together.

From the above description taken in connection with the accompanying drawings, it will be readily apparent that when it is desired to adjust the movable jaw 14 with respect to the rigid jaw 3, the knob 11 is grasped and the screw 7 rotated, the threads thereon co-acting with the threads 17 formed in the concave recess 16 whereby the movable jaw will be quickly and readily adjusted toward or away from the rigid jaw.

It will be apparent from the description taken in connection with the accompanying drawings that the device is extremely simple in construction and can be manufactured at a comparatively low cost.

While I have shown and described the preferred form of my invention, it will be obvious that various changes in the details of construction and in the proportions may be resorted to for successfully carrying my

invention into practice without sacrificing any of the novel features or departing from the scope of the appended claim.

What I claim is:—

- 5 A device of the class described including a rigid shank, having a jaw formed at its outer end, a handle member formed integral with the shank and provided in its face with a recess and further provided with a longitudinal bore communicating with said recess, a screw member arranged within said recess having a central bore communicating with the bore in the handle, a movable shank having a jaw opposed to the rigid jaw, the inner edge of said handle member having a substantially convex surface, said movable shank having a concave longitudinal recess adapted to receive the convex portion of the
- 10
- 15

handle member, screw threads formed on the ends of said concave recess and adapted to 20 coact with the screw, and a rod arranged within the bores formed in said screw and handle member and provided with a knob whereby said screw may be rotated to adjust the movable jaw with respect to the rigid 25 jaw, and a metallic band encircling said handle member and movable shank, whereby to prevent lateral movement of either member.

In testimony whereof I hereunto affix my 30 signature in the presence of two witnesses.

JOSEPH VALIND.
